UNITED STATES PATENT OFFICE

169,997

BROOCH OR SIMILAR ARTICLE

Florence C. Witmer, New York, N. Y.

Application June 26, 1952, Serial No. 20,368

Term of patent 14 years

(Cl. D45—19)

To all whom it may concern:

Be it known that I, Florence C. Witmer, a citizen of the United States, residing at New York, in the county and State of New York, have invented a new, original, and ornamental Design for a Brooch or Similar Article, of which the following is a specification, reference being had to the accompanying drawing constituting a part hereof:

Fig. 2 is a side elevational view thereof.

I claim:

The ornamental design for a brooch or similar article, substantially as shown.

FLORENCE C. WITMER.
